UNITED STATES PATENT OFFICE.

THOMAS SMALL, OF CHICAGO, ILLINOIS.

CAR-FENDER.

SPECIFICATION forming part of Letters Patent No. 632,068, dated August 29, 1899.

Application filed April 10, 1899. Serial No. 712,467. (No model.)

To all whom it may concern:

Be it known that I, THOMAS SMALL, a citizen of the United States, residing at Chicago, in the county of Cook and State of Illinois, 5 have invented a new and useful Improvement in Car-Fenders, of which the following is a specification.

My object is to provide a car-fender of an improved construction whereby the danger of 10 injury to animate bodies struck by it may be reduced to a minimum.

In carrying out my invention I provide a 15 pivotally-mounted fender-frame with a yielding forward edge portion and supported normally when in use to extend at its forward portion a desired distance above the road-bed, the supporting means for the frame being operative to release the same under an impact against the yielding forward edge portion, 20 whereby the forward part of the frame will drop to or close to the road-bed. Incidentally I provide improved means for maintaining the fender normally at a desired level with relation to the tracks without regard to variations in the relative level of the car-body 25 under change of load or change in grade. I also provide the fender of a construction whereby it may be readily folded out of the way when not in use and with other features, 30 all as hereinafter set forth, which tend to render the fender economical to construct, strong, durable, and well adapted for its purpose.

Referring to the accompanying drawings, 35 Figure 1 is a side elevation of my improved fender applied to a car-body, only enough of the latter being shown to illustrate the mode of attachment; Fig. 2, a plan view of the fender; Fig. 3, a section taken on the irregular 40 line 3 of Fig. 1 and viewed in the direction of the arrow; Fig. 4, a sectional plan view on line 4 of Fig. 1; Fig. 5, a section on line 5 of Fig. 2, showing the fender released from its support and dropped to the road-bed; and 45 Fig. 6 a sectional view corresponding with that shown in Fig. 5, but illustrating the fender in its folded position.

A is a car-body, and B the fender.

t t are brackets secured in any suitable 50 manner to the car-body and provided at their forward ends with vertical sleeves t'.

The back frame B' of the fender consists of a top bar s and legs s' s', which pass loosely

downward through the sleeves t', a cross-bar s² below the sleeves t', and a lower bar or 55 shaft s³, carrying rollers s⁴, which rest and run upon the track X. The shaft s³ is loosely mounted in the lower ends of the legs s', and the rollers are journaled thereon. Surrounding the legs s' and confined between the 60 sleeves t' and sleeves s⁵ at the ends of the cross-bars s² are springs s⁶, which tend to press the back frame of the fender downward to maintain the rollers s⁴ in contact with the track under variations in the level of the car- 65 body A. It will be understood that the car-body A is mounted upon springs on the car-axles and yields under variations in the load.

B² is a pivotal frame forming part of the fender and consisting of side bars p p and 70 cross-bars p' p². The side bars p are fastened to the shaft s, and the bar p is formed, preferably at its center, with a loop or stirrup p³. At opposite sides of the stirrup are brace-bars p⁴ p⁴, which engage the shaft s³ and bars 75 p' p², as shown, to strengthen the frame. At the forward end of the frame B² is a shaft n, carrying rollers n' n'. These rollers may be of wood or metal and of small diameter.

B³ is a frame extension consisting of side 80 bars l l, pivoted upon the shaft n and having shoulders l', which rest against similar shoulders on the end portions of the bars p when the bars l extend in direct line with the bars p. Springs l² on the shaft n and engaging 85 the side bars l tend to hold the latter yielding down and permit them to yield upward in the event of their striking obstructions. To facilitate this, the forward ends of the bars l are cam-shaped, as shown at l³. Fastened 90 at opposite ends to the respective bars l is a preferably rubber tube or strip k, forming a soft and yielding forward edge portion for the fender.

B⁴ is a spring-supporting arm or catch piv- 95 otally mounted at one end upon the bar s at the center of the latter. Toward its lower free end the catch B⁴ presents a shoulder i and beyond the said shoulder a bearing-surface i'. The catch B⁴ extends downward and 100 forward from the bar s, with its shoulder i in position to engage the stirrup p³ and sustain the frame B² at a desired level above the track, as shown, for example, in Fig. 1. The catch is prevented from accidentally releas- 105 ing itself from the stirrup p³ by springs i²,

coiled about the bars s and bearing against the catch to press it in the forward direction. Fastened at its forward end portion to the yielding strip k is a rod h , which passes loosely through guide-openings in the shaft n and cross-bars p^2 into contact with the bearing-face i' of the catch B^4 . Any backward yielding of the strip k presses the rod h in the backward direction and causes it to press back the catch B^4 to release the stirrup p^3 and cause the swinging frame B^2 to drop to the position shown in Fig. 5, whereby its forward end portion rests at the rollers n' upon the road-bed. The frame may be provided with a net or a sheet of fabric B^5 , which may be fastened, as shown, to the bars s p^2 .

When it is desired to fold the fender out of the way, the catch B^4 may be released from the stirrup p^3 and raised and the frame B^2 swung upward upon its pivot at s^3 , all as shown in Fig. 6. The catch B^4 may be caused to pass through an opening y in the netting B^5 and the fender fastened in folded position by any suitable means.

When the fender is in its operative position, as shown in Fig. 1, the frame B^2 extends horizontally at a distance above the track of from four to six inches to override any small obstacles that may be upon the road-bed. Should a person, child, or adult be struck by the fender, the soft yielding edge portion k will do no material injury to his body and by yielding backward will release the frame B^2 from the catch, whereby it drops as described. Thus in the further movement of the car the danger of his feet and legs being overridden by the fender, with consequent danger of injury to him, will be obviated, and he will fall against the net or bed B^5 . When the frame drops, the rollers will tend to cause it to override small obstructions, such as stones, on the road-bed, and in the event that the ends of the arms l strike obstructions at their cams l^3 they will swing upward against the resistance of the springs l^2 . Should the yielding strip k pass over the feet of a person, the frame will still drop at its rollers to the road-bed, owing to the pivotal nature of the extensions l . I do not wish to limit my invention to the use of the catch described or to the specific mechanisms shown, as the construction may be variously modified without departing from the spirit of my invention as defined by the claims.

What I claim as new, and desire to secure by Letters Patent, is—

1. In a car-fender, the combination of a pivotal frame having a yielding forward edge portion formed of a strip of soft and flexible material stretched across the frame, a movable supporting-catch for the frame and a catch-releasing rod connected with the yielding edge portion between the ends thereof to disconnect the catch and frame under backward pressure against the said yielding edge, substantially as and for the purpose set forth. 60

2. In a car-fender, the combination of a pivotal frame having side bars and a yielding forward edge portion formed of a strip of rubber stretched between and fastened at opposite ends to said side bars, a movable supporting-catch for the frame, and a catch-releasing rod connected with said rubber strip between the ends thereof to disconnect the catch and frame under backward pressure against the said rubber strip, substantially as and for the purpose set forth. 70

3. In a car-fender, the combination of a pivotal frame having a yielding forward edge portion, a swinging catch B^4 engaging and supporting said frame, and a catch-disengaging rod connected with the said yielding edge portion, substantially as and for the purpose set forth. 80

4. In a car-fender, the combination of a vertically-movable back frame attached to the car and provided with rollers which move upon the track, and a forward-extending frame pivotally connected to said back frame, said forward-extending frame having a yielding forward edge portion and normally supported to extend more or less horizontally above the plane of the track and movable downward from said position under backward pressure 90 against the yielding edge, substantially as and for the purpose set forth. 95

5. In a car-fender, the combination of the sleeves t fastened to the car, back frame B' having a top bar s , legs s' passing through said sleeves, rollers s^4 , and springs s^6 pressing the rollers to the track, frame B^2 pivoted to the frame B' , catch B^4 on the said top bar engaging and supporting the frame B^2 in a raised position, frame extension B^3 pivoted to the frame B^2 and having a yielding edge k , and catch-disengaging rod h connected with the yielding edge k , all constructed and arranged to operate substantially as and for the purpose set forth. 100 105

THOMAS SMALL.
